[57] **CLAIM**

The ornamental design for a stand for a circular saw, as shown and described.

DESCRIPTION

FIG. 1 is a front left-side view of a stand for a circular saw showing my new design;

FIG. 2 is the same perspective view of FIG. 1, the stand shown holding a circular saw (in phantom);

FIG. 3 is a perspective view of the stand of FIG. 1, the stand having been rotated 180 degrees;

FIG. 4 is a top view of the stand for a circular saw of FIG. 1;

FIG. 5 is a front view of the stand for a circular saw of FIG. 1, the back view being identical;

FIG. 6 is a bottom view of the stand for a circular saw of FIG. 1; and,

FIG. 7 is a left side view of the stand for a circular saw of FIG. 1.

The broken line showing of the circular saw is for illustrative purposes only and forms no part of the claimed design.
